DESIGN FOR A JEWELRY PIN

George Stangl, New York, N. Y., assignor to Jay Kel Jewelry Co., New York, N. Y., a copartnership

Application August 8, 1945, Serial No. 121,318

Term of patent 3½ years

(Cl. D45—19)

To all whom it may concern:

Be it known that I, George Stangl, a citizen of the Republic of France, and resident of the city, county, and State of New York, have invented a new, original, and ornamental Design for a Jewelry Pin, of which the following is a specification, reference being had to the accompanying drawing forming a part hereof, in which

Fig. 1 is a front elevation of a jewelry pin, showing my new design, and Fig. 2 is a side elevation of the same.

I claim:

The ornamental design for a jewelry pin, substantially as shown.

GEORGE STANGL.
